UNITED STATES PATENT OFFICE.

ELIAS P. MASTERSON, OF PORT JERVIS, NEW YORK.

PHOTOGRAPHIC PRINTING-FRAME.

SPECIFICATION forming part of Letters Patent No. 245,851, dated August 16, 1881.

Application filed June 10, 1881. (No model.)

To all whom it may concern:

Be it known that I, ELIAS PERRY MASTERSON, of Port Jervis, in the county of Orange and State of New York, have invented certain new and useful Improvements in Photographic Printing-Frames; and I do hereby declare the following to be a full, clear, and exact description of the invention, such as will enable others skilled in the art to which it pertains to make and use it, reference being had to the accompanying drawings, which form part of this specification.

My invention relates to an improvement in photographic printing-frames; and it consists, first, in a hinged cover having grooves made along its edges and provided with spring holding-wires, so as to hold the picture in place; second, in movable wedges which are passed through the edges of the frame, and which serve to raise the cover up far enough to break contact between the negative and the paper and hold the parts thus separated.

Figure 1 is a vertical section of my invention. Fig. 2 is a perspective of a portion of the cover, showing the spring-clamps for holding the paper to the cover. Fig. 3 is a plan view of the frame, showing the springs for holding the vignette in place, and the screw-clamp for holding the negative in place.

A represents the frame, which is of the usual construction, and B the cover, which is made in two parts hinged together. Instead of having this cover entirely separate and distinct from the frame, the cover is here hinged or otherwise attached to the frame at one end, so that the frame will always occupy exactly the same space when closed down upon the negative. Where the cover is made separate from the frame there is always a liability of its moving slightly, in which case the paper will be shifted upon the negative, and thus the image produced will be ruined. By hinging the cover at one end no movement can possibly take place, and thus the picture produced will always be a perfect one.

In order to attach the paper that is to be printed upon to the inner side of the cover a spring-clasp, D, is used at each edge of the cover, as shown. This spring-clasp consists of a bent spring-wire, which is fastened permanently at one edge of the cover, and which

has its free end bent, as shown, so as to catch over the outer edge of the cover while holding the paper in place. As soon as these ends are forced past the edge of the cover they 55 spring outward sufficiently far to release the paper entirely. In order to enable these springs to hold the paper in position—in such a manner that it will be impossible to accidentally displace it—a groove, E, is cut along each side 60 near the edge of the cover, and the springs force the paper down into these grooves. By thus combining the two features of a cover which is hinged to the frame at one end, and spring-clasps which lock the paper in position, 65 it will readily be seen that however often the contact may be broken between the negative and the paper the paper will always be returned to exactly the same position under any circumstances.

In order to hold the negative in position the slide F, which is forced forward by the set-screw G, is used. The slide has its ends grooved, so as to catch over suitable guiding-catches formed on the inner side of the frame, 75 and that part of the slide which comes in contact with the end of the negative is also grooved, so as to catch over its end. When the set-screw is forced forward the slide forces the negative tightly against the frame and 80 holds it there so rigidly that it is impossible for it to be moved until the slide has been loosened, unless the glass is broken.

Passed horizontally through the sides of the frame at different points are the wedge-shaped 85 pins H, which can be forced inward so as to catch just under the edge of the cover and raise the cover upward just far enough to break the contact of the paper and the negative. These pins may be held in position in a 90 number of different ways; but I prefer to make a slot in each pin, then pass a wire or other stop down through the frame, and this slot will serve to prevent the pin being moved too far in either direction. Three pins are here shown, 95 but it is evident that any desired number of them may be used.

In order to secure the vignette to the frame a spring-wire, I, is used upon each edge of the frame, which wires have their outer ends 100 bent so as to catch over suitable projections prepared for them. Whenever it is desired to

fasten a vignette, card, or paper of any kind to the frame it is only necessary to place it across the frame and then bear down upon the spring-wires in such a manner as to cause their 5 ends to fasten upon the projections.

Having thus described my invention, I claim—

1. The combination of the cover, provided with a groove along its edge, with spring-wires 10 for securing the paper in position, substantially as set forth.
2. The combination of the frame, the cover, and suitable slotted pins or wedges, which are

passed through the frame and made to catch under the cover so as to raise the paper out of 15 contact with the negative, substantially as shown.

In testimony whereof I affix my signature in presence of two witnesses.

ELIAS PERRY MASTERSON.
